UNITED STATES PATENT OFFICE.

HENRY J. HESS, OF ILION, NEW YORK.

HALTER.

SPECIFICATION forming part of Letters Patent No. 247,912, dated October 4, 1881.

Application filed August 18, 1881. (No model.)

To all whom it may concern:

Be it known that I, HENRY J. HESS, a citizen of the United States of America, residing at Ilion, in the county of Herkimer and State of New York, have invented certain new and useful Improvements in Halters; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

This invention relates to halters for animals; and the improvement consists in the straps riveted to the metallic plates, having projections; also the buckles attached to said metallic plates, as will be hereinafter more fully described, and particularly pointed out in the claim.

In the accompanying drawings, Figure 1 represents my improvement applied to the halter of a horse. Figs. 2 and 3 represent plans of the metallic joints as usually formed.

As shown in the drawings, the metallic plate A is formed like a ring, with flat projections a a' a'' radiating from its center, such projections having holes in them, so that the ends of the straps c may be fastened to them by means of rivets, instead of fastening the parts together by means of stitching, as is the common practice.

In Fig. 3 is shown the form of plate A' for

use at the joint of straps near the horse's ear, where the halter is buckled. In this form one of the projections, a^3 , is provided with a buckle, B, being made fast to a cross-bar of the buckle, or made solid therewith, while the other projections, a^4 and a^5 , are to rivet the straps to, as in the case of a , a' , and a'' . A metallic piece, b, having a loop at each end, is provided, to hold the two straps which pass under the horse's head and neck in position.

By the use of this device for joining the ends of straps farmers and others in rural districts are enabled to do much of their repairing of halters and headstalls, and such repairing may be quickly effected, it being only necessary to fasten with rivets the ends of the straps to the plate A.

I claim—

In a halter, the straps c, riveted to the metallic plates A, having projections a , a' , and a'' , in combination with the plate A', having the arm a^3 , to which the buckle B is secured, and also the projections a^4 and a^5 , to which the straps c are riveted, and provided with the rigid loop-piece b, the whole constructed and arranged substantially as set forth.

In testimony whereof I affix my signature in presence of two witnesses.

HENRY J. HESS.
